UNITED STATES PATENT OFFICE.

BICK R. BONNEY, OF OMAHA, NEBRASKA, ASSIGNOR OF ONE-THIRD TO JAMES W. ELWOOD AND ONE-THIRD TO C. F. BETCKE, BOTH OF OMAHA, NEBRASKA.

ROAD-MAINTAINER.

1,357,685.

Specification of Letters Patent. Patented Nov. 2, 1920.

Application filed November 8, 1919. Serial No. 336,564.

To all whom it may concern:

Be it known that I, BICK R. BONNEY, a citizen of the United States, residing at Omaha, in the county of Douglas and State 5 of Nebraska, have invented certain new and useful Improvements in Road-Maintainers, of which the following is a specification.

This invention relates to an improvement in road maintainers, and has for its object, 10 broadly, to provide such a construction that all rough parts of a roadway may be readily removed, and depressions or pockets may be filled, and that a suitable curvature in cross-section will be formed while the machine 15 moves forwardly, the parts being so arranged that the stresses directed to the vehicle frame will be sustained to advantage, and that a strong construction may be provided having a comparatively light weight, 20 one of the specific objects being to provide means under suitable control for cutting and loosening the ground in the roadway at the front of the scraper-blades.

The invention consists of the novel construction, combination and arrangement of parts as described herein and claimed, and as illustrated in the accompanying drawing, wherein,—

Figure 1 is a plan view of a road maintainer embodying my invention. Fig. 2 is a side view of the same. Fig. 3 is a front view and Fig. 4 is an end view of a drag or scarifier. Fig. 5 is a plan view of a scarifier provided with a tongue, a tilting-bar 35 and a pair of adjusting-bars. Fig. 6 is a view in side elevation of the tongue and bars shown in Fig. 5 and an end view of the scarifier. Fig. 7 shows an end view of a pair of connected scraper-blades. Fig. 8 is 40 a broken away view showing the front sides of a pair of scraper-blades. Fig. 9 is a view of the parts shown in Figs. 5 and 6, the teeth of the scarifier being swung to a position above the tongue.

In the drawing, numeral 1 indicates a 45 main frame approximately of U-shape in plan, the "off" side of said frame having a lesser length than the "near" side, said frame being provided with front wheels 2, and provided at its rear ends with caster-wheels 3. Numeral 4 indicates a cross-plate, 50 said plate being disposed closely adjacent to and forwardly of the caster-wheels and secured to the U-shaped frame, said cross-plate, therefore, being disposed in inclined 55 relation to the longitudinal axis of the ve-

hicle. Numeral 5 indicates a platform upon which an operator may stand, said platform, preferably, being disposed parallel with and rearwardly of the cross-plate 4.

I provide an underframe consisting of an angle-bar or second cross-plate 6 and suitable hangers 7, said plate 6 being disposed parallel with the plate 4 and being supported principally by the main frame, suitable stay-rods 8 being provided for said plate 6 and connected with the front bolster 9.

At 10 are indicated a plurality of scraper-blades, each being disposed approximately parallel with the plates 4 and 6, each blade being provided with a pair of draw-bars 11 which extend forwardly for a pivotal connection with an eye-bolt 12, the latter being mounted in and at longitudinal intervals of the plate 6, the adjacent ends of the blades 15 being pivotally connected by means of wrist-pins 13, or equivalent means.

Means are provided for disposing and maintaining the scraper-blades at higher or lower altitudes, this being necessary so that 80 they may suitably engage in the ground, and also may be elevated during operation while "turning about" as well as when driving over bridges or obstructions, said means consisting of horizontal shafts 14 disposed in suitable bearings at the upper 85 side of the cross-plate 4, said shafts being revoluble by hand-levers 15, conventional, toothed sectors 16 being employed and secured to said cross-plate to be engaged by pawls 17 which are provided for the hand-levers, one of the toothed sectors 16', as best shown in Fig. 1, being mounted on the U-shaped frame, its hand-lever 15' being provided with a link 18 which is connected 90 with an upright lever 19, and it will be understood that a swinging movement of said hand lever 15' will cause a swinging movement of the lever 19 for causing a rotatable movement of the horizontal shaft 20. 95

Each of the shafts 14 and 20, preferably, are provided with a crank or angularly disposed arm *a* for a connection with an upright connecting-rod *b*, each rod *b*, as best shown in Fig. 7, being movably secured to 105 a scraper-blade adjacent to the end thereof, and it will be understood that a revoluble movement of the shafts 14 and 20, in one direction, will cause the blades 10 to move upwardly, and that they may be maintained 110 in their elevated position since the pawls of the hand-levers may engage the toothed sec-

tors, said scraper-blades moving downwardly by their own weight when the pawls 17 are released from the toothed sectors, and also adapted to be forced into the ground 5 a suitable distance by use of the hand-levers.

On account of the construction described, the scraper-blades may be elevated at various, required heights to conform to a desired, curved shape of a road bed in cross-section, and the blade which is disposed nearest to the "off" side of the vehicle may be disposed at such inclination that a ditch or gutter may be conveniently formed; and it will be understood that since the scraper-blades are disposed in inclined relation to the longitudinal axis of the vehicle, the ground or a part thereof, when the vehicle moves forwardly, may be conducted toward the "near" side of the vehicle, to form a highway having its highest part at its middle.

In order that the ground may be cut and loosened at the front of the scraper-blades, I provide a plurality of drags or scarifiers, 25 each consisting of a bar or angle-iron 21 provided with teeth 22, tongue-members 23 being provided for the bars to extend forwardly for a pivotal mounting in suitable brackets α (Fig. 2) which are secured to the 30 cross-plate 6. Each angle-bar 21 is provided with a pair of adjusting-bars 24, the lower ends of the latter having pivotal mountings α' in the upset arms g of the tongue-members 23. The adjusting-bars 24 are adapted 35 to be connected with the draw-bars 11, between the ends of the latter, a plurality of apertures e being provided at longitudinal intervals in the bars 24, as best shown in 40 Figs. 2, 6 and 9, and bolts d (Fig. 2.) being used which engage in apertures e (Fig. 7.) of the bars 11, whereby the scarifiers may be 45 adjusted to be disposed nearer to or farther from the bars 11, at greater or lesser distances from the ground; this being of great advantage when working upon wet roads or upon dry roads which have become packed and hardened.

Since each bar 24 is adjustably mounted upon a bar 11 of a scraper-blade, it is obvious that one of the ends of each scarifier 50 may be maintained at a greater altitude than its opposite end, so that it may conform approximately to the required curvature of a road-bed in cross-section.

According to the described construction, 55 it will be understood that the operation of elevating a scraper-blade will cause an elevation of a scarifier, and when the blades are moved downwardly, by use of the hand-levers, the scarifiers will also have a downward movement for causing the teeth to engage somewhat deeper in the ground.

I provide means for elevating the teeth of each scarifier above the ground and 60 above the tongue 23, said means consisting,

in part, of a tilting-bar 25 which is secured to the angle-bar 21, the latter being provided with brackets 26 upon which the upset arms g of tongue-members 23 are pivotally mounted, as indicated at h , to permit 70 swinging movements of the parts, rearwardly extending pull-and-push rods 27 being connected with the tilting-bars and extending rearwardly to the platform 5, for use of an operator, any suitable means being provided 75 for removably securing the rods 27 to the platform after the bars 21 together with the teeth 22 have been swung to the position shown in Fig. 9, the means shown herein consisting of certain forked plates m which are secured to the cross-plate 4, in which the rods 27 are slidably mounted, each rod being provided with a cross-pin n adapted to be lifted over the top of a plate m when the rod is moved rearwardly, and to then 80 engage the rear side of said plate m to prevent a forward movement of the pull-and-push rod.

The advantages to be derived by operation of the scarifiers will be appreciated by users 90 of the road maintainer as described, since the scraper-blades may not readily enter ground which has become packed and hard, and therefore may fail to remove all of the 95 ridges or hardened areas, but since the scarifiers are disposed forwardly of the scraper-blades at right angles to the line of travel of the vehicle, the toothed bars operate to cut into the hardened ridges and solid areas of the road-bed, the blades operating to form 100 a comparatively smooth surface and conducting the loose earth toward the medial line of the road-bed.

While I have described specifically the desired construction, it will be understood that 105 I may change minor details, and also may change size, form and proportion of parts as may be found to be of advantage, these changes, in character and degree, being determined by the scope of the invention as 110 claimed.

I claim:

1. In a road maintainer, a frame provided with wheels, draw-bars pivotally connected with the frame, scraper-blades rigidly connected with the draw-bars, toothed bars disposed forwardly of the scraper-blades and pivotally connected with the frame and said draw-bars, means movable to permit the scraper-blades and toothed bars to have 115 simultaneous downward movements, said means also being movable to cause the scraper-blades and toothed bars to have simultaneous upward movements.

2. In a road maintainer, the combination 120 with a vehicle having a main frame and an underframe, draw-bars arranged in pairs and pivotally connected with the underframe, a plurality of scraper-blades each being rigidly mounted upon a pair of draw- 125 bars, each scraper-blade having a toothed bar 130

bars, wrist-pins connecting the scraper-blades, connecting rods engaging the scraper-blades and being movable for elevating the draw-bars and said blades and for 5 moving them toward the ground, and means to prevent an upward movement of the scraper-blades after they have been moved toward the ground.

3. In a road maintainer, the combination 10 with the frame of a vehicle, draw-bars arranged in pairs and pivotally connected with the frame to extend rearwardly thereof, scraper-blades disposed transversely of the road with their ends adjacent to each other, 15 wrist-pins pivotally connecting the adjacent ends of said blades, connecting-rods projecting upwardly from the scraper-blades and mounted thereon adjacent to the wrist-pins, means for moving the connecting-rods down- 20 wardly to move the blades into the ground and means for preventing an upward movement of said blades.

4. In a road maintainer, a frame provided 25 with wheels, draw-bars pivotally connected with the frame, scraper-blades rigidly connected with the draw-bars, toothed bars pivotally connected with the frame and draw-bars means to maintain the toothed bars at predetermined distances from the

draw-bars, means movable to permit the 30 scraper-blades and toothed bars to have simultaneous downward movements, said means also being movable to cause the scraper-blades and toothed bars to have simultaneous upward movements. 35

5. In a road maintainer, a frame provided with wheels, draw-bars pivotally connected with the frame, tongue-members pivotally connected with the frame, links adapted to be pivotally connected at selected intervals 40 of their lengths with the draw-bars and pivotally connected with the tongue-members, scraper-blades rigidly connected with the draw-bars, toothed bars disposed forwardly of the scraper-blades, said toothed bars being 45 pivotally connected with the tongue-members and with said links, means movable to cause simultaneous swinging movements of the scraper-blades and tongue-members, and a plurality of pull-and-push rods for 50 moving the toothed bars in a circle's arc.

In testimony whereof, I have affixed my signature in presence of two witnesses.

BICK R. BONNEY.
